UNITED STATES PATENT OFFICE.

JOSEF DECHESNE, OF ROSTOCK, GERMANY.

CUPOLA OR HEARTH FURNACE.

Application filed March 10, 1926, Serial No. 93,593, and in Germany January 26, 1925.

My invention relates to improvements in cupola or hearth furnaces, and the object of the improvements is to provide a furnace in which gas and other foreign matter such as sulfur are separated from the molten iron. With this object in view my invention consists in providing means for shaking or otherwise agitating the fore-hearth of the cupola or hearth furnace. One way of stirring the fore-hearth consists in uniformly lifting and dropping the same. But I have found that the separation of the gas and other foreign matter is made more effective by constructing the stirring means in such a way that the fore-hearth is lifted to different heights. Thereby the surface of the iron bath is formed into waves of different lengths, and the lengths of the said waves can be regulated so that the successive waves impinge upon each other and are strengthened, so that the agitation of the iron bath is comparatively vivid.

For the purpose of explaining the invention an example embodying the same has been shown in the accompanying drawing, in which the same reference characters have been used in all the views to indicate corresponding parts. In said drawing,

Fig. 1 is a sectional elevation showing the bottom part of the cupola furnace, the fore-hearth and means for agitating the same, and

Fig. 2 is an elevation looking from the left in Fig. 1.

In the example shown in the figures the cupola furnace *a* is provided with conduits *c* and tuyères *d* for supplying air thereto, and with a tap hole *e* for delivering the molten iron to the top part of the fore-

hearth *f*. The fore-hearth is covered by a lid *g*, and it is provided at its bottom with a tap hole *h*. The pipe *e* forming the tap hole of the cupola furnace has a certain clearance in the wall of the fore-hearth *f*.

At the side of the cupola furnace the fore-hearth *f* is supported by means of spherical pivots *i* on bearing blocks *k*, and at its front side it is supported on a pair of cam disks *m* carried by a rotary shaft *n*. Preferably the cam disks are mounted on the shaft so as to be adjustable thereon. The shaft *n* is mounted in bearings *o*, and it is adapted to be rotated by means of a belt-pulley *p*. As shown, each cam disk *m* is provided with

two cams *r* and *s*, and the said cams have 55 different distances from the axis of the shaft *n*.

In the operation of the cupola furnace *a* the iron is intermittently tapped from the fore-hearth. By the rotation of the shaft 60 *n* the fore-hearth *f* is alternately elevated and dropped at its front end by the cam disks *m*, and it is rocked about the bearing blocks *k*. The fore-hearth is elevated by the cams *r* to a greater height than by the cams *s*. 65

After tapping the fore-hearth *f* the iron coming from the cupola furnace *b* is stirred by the agitation of the fore-hearth *f*, and the particles of iron are whirled relatively to one another, so that the gas contained within the 70 iron rises to the surface thereof and the manganese molecules are brought into contact with the sulfur molecules, and the sulfur manganese slag rises to the surface.

Since this agitation takes place while the 75 iron rises within the fore-hearth *f*, the gas and slag are separated at the surface of the bath, so that the resistance opposed thereto is comparatively small. Further, the temperature of the iron bath is maintained, because the hot gases coming from the cupola furnace flow over the surface of the iron delivered into the hearth. Thereby the gas and slag are readily separated.

The same conditions prevail as the flow of 85 the iron into the fore-hearth is continued, because the mass of iron at the bottom of the hearth is already free of gas and foreign matter when the new mass of iron is delivered into the fore-hearth, and the new 90 mass of iron is always at the surface of the bath which is subject to the most vivid agitation.

The waves produced by the cams *r* and 95 *s* within the bath of iron have different lengths, so that the whirls are strengthened by interference of the waves of different lengths meeting each other. The said whirls can be controlled by providing cams of different sizes and different relative positions.

I am aware that it has heretofore been proposed to separate gas and other foreign matter from the iron by stirring the same in ladles. But I have found that in my improved furnace the separation of the said foreign matter is more effective for the following reason:

The fore-hearth is directly connected with

the furnace, and the iron molten within said furnace is continuously delivered into the fore-hearth. When flowing into the fore-hearth the gases of the cupola furnace flow over the iron and keep the same at high temperature. At such high temperature the gas is readily separated from the iron, and a large proportion of the sulfur is bound to the manganese, the proportion being considerably higher than in ladles in which the iron is gradually cooled and crystallized, the reduction of the temperature interfering with the separation of the sulfur and other gases. Further, as the fore-hearth is gradually filled the lower layers of the bath of iron are always freed of the gas and other impurities, while the upper layers of the bath which have been recently delivered into the fore-hearth are not yet freed of the gas and the impurities. Now, when shaking the fore-hearth, the uppermost layer of the bath is subject to vigorous agitation, so that the particles of the iron are stirred and almost all the molecules of manganesees are brought into contact with the sulfur molecules. Further, the path of the slag of sulfur manganese and the gas through the bath of iron is comparatively small, so that the resistance opposed to the separation of the said slag and gas is small.

While in describing the invention reference has been made to a particular example embodying the same I wish it to be understood that my invention is not limited to the construction shown in the drawing, and that various changes may be made in the general arrangement of the apparatus and

the construction of its parts without departing from the invention.

I claim:

1. The combination with a furnace for melting metal, of a fore-hearth directly connected with said furnace for receiving the molten metal therefrom, and means to shake the said fore-hearth.

2. The combination with a furnace for melting metal, of a fore-hearth directly connected with said furnace for receiving the molten metal therefrom, and means to impart varying agitating movement to the fore-hearth.

3. The combination with a furnace for melting metal, of a fore-hearth directly connected with said furnace for receiving the molten metal therefrom, and means for successively lifting and dropping the fore-hearth.

4. The combination with a furnace for melting metal, of a fore-hearth directly connected with said furnace for receiving the molten metal therefrom, and means for successively lifting the fore-hearth to different heights and dropping the same.

5. The combination with a furnace for melting metal, of a fore-hearth directly connected with said furnace for receiving the molten metal therefrom, said fore-hearth being rockingly supported at the side of the furnace, and means for successively elevating and dropping the fore-hearth at its front end.

In testimony whereof, I hereunto affix my signature.

JOSEF DECHESNE.
